UNITED STATES PATENT OFFICE.

JOHN C. POFFENBARGER, OF PEORIA, ILLINOIS.

INKING ATTACHMENT FOR PRINTING-PRESSES.

1,167,928.

Specification of Letters Patent. Patented Jan. 11, 1916.

Application filed August 28, 1914. Serial No. 859,018.

To all whom it may concern:

Be it known that I, JOHN C. POFFENBARGER, a citizen of the United States, and a resident of Peoria, in the county of Peoria 5 and State of Illinois, have invented new and useful Improvements in Inking Attachments for Printing-Presses, of which the following is a specification.

My invention relates to improvements in printing presses and particularly to inking attachments therefor, the principal object being to provide a construction wherein in the ordinary platen printing presses, a uniform distribution of ink may be readily obtained.

A further object of the invention is the provision in a press of the type mentioned, of an ink distributing cylinder and suitable mechanism for operating the parts to secure 20 efficient distribution of the ink.

Another object of this invention is the provision in printing presses, of an ink distributing cylinder, means for driving the same and form inking rollers and means for 25 moving said form inking rollers over the form and in contact with said cylinder and for holding said rollers in contact with the cylinder for several revolutions.

A further object of the invention is the 30 provision of such a construction which may be readily arranged or attached to existing standard forms of platen presses without the necessity of reconstructing or rearranging them.

To the accomplishment of the foregoing and such other objects as may hereinafter appear, my invention consists in the combination, construction and arrangement of parts hereinafter described, and then sought 40 to be defined in the appended claims, reference being had to the accompanying drawings forming a part hereof, and which shows merely for the purpose of illustrative disclosure, a preferred embodiment of my invention, it being understood that various 45 changes may be made in practice within the scope of the claims, without digressing from my inventive idea.

In the drawings, Figure 1 represents a 50 rear elevation of an ordinary form of platen press with my invention applied thereto, parts being broken away to facilitate disclosure; Fig. 2 is a view of the press having my invention applied thereto, the press being shown in open position and parts being broken away to facilitate disclosure; Fig. 3

is a view similar to Fig. 2, the parts being shown closed; Fig. 4 is a detailed view of a roller wing carrying the rollers and connections for operating the same, the parts being 60 shown in a position assumed when the press is closed; Fig. 5 is a view similar to Fig. 4, the parts being shown in a position assumed when the press is open; Fig. 6 is a detailed view of the means for shifting or vibrating 65 the ink distributing cylinder.

As at present constructed with the disk form of ink distribution, the ordinary platen job presses are faulty, due to the inefficient distribution of ink and it is the principal 70 object of my invention to improve this distribution. I do this, by mounting an ink distributing cylinder in place of the disk, so that an effective transfer of the ink from the fountain to the inking roller occurs. In 75 supplying this idea to existing forms of presses, it is only necessary to remove certain parts and add others, the construction being readily adaptable for substitution in these presses.

In the drawings, I have illustrated merely one form of the standard forms of platen presses, it being understood as stated above, that my invention is applicable to other forms of this type.

In these drawings, the numeral 1 designates the main frame of the press having the platen 2 mounted thereon and having the bed frame 3 also mounted thereon to swing to and fro as is well understood, the bed being indicated as 4.

5 designates the main driving shaft, having the bevel gear 6 thereon meshing with bevel gear 7 on the end of the downwardly extending shaft 8, which shaft has the bevel 95 gear 9 meshing with bevel gear 10 which is loose on the lower shaft 11, this being the shaft on which the bed carrying frame is pivoted. Bevel gear 12 on the upwardly extending shaft 13 meshes with the other side 100 of bevel gear 10 and has the bevel gear 14 on its upper end, which meshes with the bevel gear 15 on shaft 16 having the gear or pinion 17 on its other end. It is to be understood that these shafts are suitably 105 journaled in the frame parts. This gear or pinion meshes with the idler gear or pinion 18 which in turn meshes with gear or pinion 20 secured to shaft 21 to which the ink distributing cylinder 22 is connected. This cylinder is shifted by means of the tongue or finger 23 engaging in cam groove 24 in the

hub portion thereof, as is well understood in this art. It is therefore to be seen that I have provided a connection from the main driving shaft to the ink distributing cylinder whereby the same is driven at all times during the operation of the press, it being evident that the form or type rollers are operated in substantially the same manner as heretofore and without the necessity of any reconstruction so as to take the ink from the cylinder and ink the form. These form or type rollers 25 are connected to the shanks or shafts 26 which are slidably mounted in the sockets 27 in the roller, wings or carriers 28, being held properly by means of springs, not shown. This construction is well known in this art and a detailed description thereof is not necessary, it being understood that the bed is reciprocated by means of the link 29 and crank disk 30, the wings or carriers being pivotally mounted on the shaft 29' and caused to be rotated by means of the link 31 and its connections, due to the reciprocation of the bed. I provide means for limiting the swinging movement of these wings or carriers and consequently the rollers in the form of the link 31 which is normally held downwardly by spring 32 and has the elongated slot 33 in its outer end, which slot has the recess or socket 34 at its extreme end. The pin or member 35 on the wing engages said slot so that the movement of the wing is limited. In its open position, the wing is held securely by means of the pin engaging said socket 34, as shown at Fig. 5, but when the wing is started in its upward movement, the engaging lug or member 36 lifts the link so that the pin is moved from engagement with said socket 34 and the wing travels a suitable distance so that the rollers are brought in contact with the ink distributing cylinder, as shown in Figs. 3 and 4. This is necessary, for the reason that in a construction of this character, the rollers do not have to travel so far as in the type of press where the disk form of distribution is used. Another purpose for the provision of this slot 33 is that when the roller carriage and rollers reach the upper limit of their movement and the rollers are in contact with the ink distributing cylinder, the link 31 will slide on the pin or member 35 so as to produce a "dwell" in the movement of the carriage and rollers and thereby hold or lock the rollers in contact with the ink distributing cylinder for several revolutions thereof, whereby an effective supply and distribution of ink are obtained. The roller carriage and rollers remain in this position, until on the return movement of the link 31, the pin or member 35 rests in the recess or socket 34. Then the downward movement of the carriage and form or type rolls will be initiated. The provision of this means for

causing the form or type rollers to dwell or remain in the stationary position in contact with the ink distributing roller, during several revolutions of the form or type rolls is very important in the effective and proper distribution of the ink. 70

Certain other details of the press are shown, but it is not believed to be necessary to describe them as they are not within the purview of this invention, it being limited 75 to the ink distribution and the operation thereof.

It is therefore seen that I have provided a construction which can be readily attached to standard forms of platen presses, whereby a uniform distribution of ink is obtained, which operates simply and efficiently to produce the desired results and which may be installed cheaply and easily. 80

It is to be noted that for the purpose 85 of illustration, I have used the type of press known to the trade as the Gordon press, as it is a standard type of machine and one which adapts itself readily for the attachment of my invention. It is to be understood that I use the ordinary form of fountain 90 for supplying the ink to the cylinder and also use the usual riders in connection with the ink distributing rolls.

As stated hereinbefore, a large number of 95 these details are omitted for the reason that they do not add anything to the disclosure and are not embodied as part of my invention.

What I claim is:—

1. In combination in a printing press, a stationary frame provided with an oscillatory platen, a main driving shaft, a bed pivoted relative to said frame, means for reciprocating said bed to and from said frame, form inking rollers mounted on said bed, an inking cylinder journaled in the upper part of said bed, connections from the main driving shaft to said inking cylinder to rotate the same, and means for moving said form inking rollers over the form and into engagement with said inking cylinder, said means being adapted to cause said form inking rollers to "dwell" or remain in engagement with said inking cylinder during 110 several revolutions of said form inking rollers. 115

2. In combination in a printing press, a stationary frame having an oscillatory platen, a main driving shaft, a shaft journaled in the lower portion thereof, a bed mounted to reciprocate on said last mentioned shaft, roller wings pivotally mounted on said bed and having inking rollers connected thereto, an inking cylinder journaled in the upper portion of said bed, connections between said main driving shaft and said inking cylinder to rotate the same, means for reciprocating the said bed, means for raising and lowering said roller wings 120 125 130

so as to move said inking rollers over the form and in contact with said inking cylinder, said means being adapted to cause said inking rollers to "dwell" or remain in engagement with said inking cylinder during several revolutions of said inking rollers.

3. In a printing press, in combination a main frame having an oscillatory platen, a main driving shaft, a shaft in the lower portion of said main frame, a bed mounted on said second mentioned shaft and adapted to reciprocate to and from said main frame, means for reciprocating said bed to and from said main frame, a roller carriage pivotally mounted on said bed, an inking cylinder journaled in the upper portion of said bed, means for rotating the said inking cylinder, and a link connection between said main frame and said roller carriage so as to 10 rotate said carriage during the reciprocation of said bed to bring the rollers in contact with said inking cylinder, said link connection including means for causing said rollers to "dwell" or remain in engagement 15 with said inking cylinder during several rotations of said rollers.

4. In a printing press, in combination, a main frame having an oscillatory platen, a main driving shaft, a shaft in the lower portion of said main frame, a bed mounted on said second mentioned shaft and adapted to reciprocate to and from said main frame, means for reciprocating said bed to and from said main frame, a roller carriage pivotally mounted on said bed, an inking cylinder journaled in the upper portion of said bed, means for operating the said inking cylinder, a link connection between said main frame and said roller carriage so as to 20 rotate said carriage during the reciprocation of said bed to bring the rollers in contact with said inking cylinder, said link connection comprising a link or arm pivoted to said main frame and having an elongated slot in its other end, said slot having a groove or recess in its extreme end, and a lug or pin on said roller carriage adapted to move in said slot and engage in said groove or recess therein.

5. In a printing press, in combination, a main frame having an oscillatory platen, a main driving shaft, a shaft in the lower portion of said main frame, a bed mounted on said second mentioned shaft and adapted to reciprocate to and from said main frame, means for reciprocating said bed to and from said main frame, a roller carriage pivotally mounted on said bed, an inking cylinder journaled in the upper portion of said bed, means for operating the said inking cylinder, a link connection between said main frame and said roller carriage so as to rotate said carriage during the reciprocation of said bed to bring the rollers in contact with said inking cylinder, said link

connection comprising a link or arm pivoted to said main frame and having an elongated slot in its other end, said slot having a groove or recess in its extreme end, a lug or pin on said roller carriage adapted to move in said slot and engage in said groove or recess therein, and means for lifting said link so that the lug or pin is removed from engagement with said groove or recess in said slot.

6. In a printing press, in combination, a main frame having an oscillatory platen, a main driving shaft, a shaft in the lower portion of said main frame, a bed mounted on said second mentioned shaft and adapted to reciprocate to and from said main frame, means for reciprocating said bed to and from said main frame, a roller carriage pivotally mounted on said bed, an inking cylinder journaled in the upper portion of said bed, means for operating the said inking cylinder, a link connection between said main frame and said roller carriage so as to rotate said carriage during the reciprocation of said bed to bring the rollers in contact with said inking cylinder, said link connection comprising a link or arm pivoted to said main frame and having an elongated slot in its other end, said slot having a groove or recess in its extreme end, a lug or pin on said roller carriage adapted to move in said slot and engage in said groove or recess therein, means for lifting said link so that the lug or pin is removed from engagement with said groove or recess in said slot, said means comprising a lug or projection on said roller carriage moved into engagement with said link by the rotation of said carriage.

7. In combination, in a printing press, a stationary frame having an oscillatory platen thereon, a main driving shaft, a shaft journaled in the lower portion of said main frame, and having a bevel gear loosely mounted thereon, connections between said main driving shaft and said bevel gear to operate the same, a bed connected to said second mentioned shaft and means for reciprocating said bed to and from said frame, a roller carriage pivotally mounted on said bed, an inking cylinder journaled in the upper portion of said bed, the rolls of said roller carriage adapted to be moved upwardly into engagement with said cylinder when the bed is in its closest position to said frame, an upwardly extending shaft journaled in said bed and geared to said bevel gear, gear connections between the upper end of said upwardly extending shaft and said inking cylinder to rotate the same, and means for vibrating the said inking cylinder.

8. In combination in a printing press, having a main frame with an oscillatory platen, a main driving shaft, a reciprocable

bed, and means to reciprocate said bed to and from said main frame, a roller carriage pivotally mounted on said bed, an inking cylinder journaled in said bed, means for rotating said inking cylinder, means for operating said roller carriage so as to move the rollers over the form and in contact with said inking cylinder, said operating means including means for causing said inking rollers to "dwell" or rest in engagement with said inking cylinder during several revolutions of said inking rollers.

9. In combination in a printing press, having a main frame with an oscillatory platen, a main driving shaft, a reciprocable bed, and means to reciprocate said bed to and from said main frame, a roller carriage pivotally mounted on said bed, an inking cylinder journaled in said bed, means for rotating said inking cylinder, means for operating said roller carriage so as to move the rollers over the form and in contact with said inking cylinder, said operating means including a link pivotally connected to said main frame and having an elongated slot in its other end, and a projection on said roller carriage adapted to move in said slot during the "dwell" of said inking rollers.

10. In combination in a printing press, having a main frame with an oscillatory platen, a main driving shaft, a reciprocable bed, and means to reciprocate said bed to and from said main frame, a roller carriage pivotally mounted on said bed, an inking cylinder journaled in said bed, means for rotating said inking cylinder, means for operating said roller carriage so as to move

the rollers over the form and in contact with said inking cylinder, said operating means including a link pivotally connected to said main frame and having an elongated slot in its other end, and a projection on said roller carriage adapted to move in said slot during the "dwell" of said inking rollers, said link also being provided with a recess in one end of said slot in which the projection is adapted to rest during the movement of said roller carriage.

11. In combination in a printing press, having a main frame with an oscillatory platen, a main driving shaft, a reciprocable bed, and means to reciprocate said bed to and from said main frame, a roller carriage pivotally mounted on said bed, an inking cylinder journaled in said bed, means for rotating said inking cylinder, means for operating said roller carriage so as to move the rollers over the form and in contact with said inking cylinder, said operating means including a link pivotally connected to said main frame and having an elongated slot in its other end, and a projection on said roller carriage adapted to move in said slot during the "dwell" of said inking rollers, said link also being provided with a recess in one end of said slot in which the projection is adapted to rest during the movement of said roller carriage, and means on said roller carriage for moving said link so as to disengage said projection from said recess.

JOHN C. POFFENBARGER.
